UNITED STATES PATENT OFFICE

154,567

DESIGN FOR A GAME BOARD

Martin Siegel, Newark, William S. Hosek, Bloomfield, and Frank L. Boucher, Millington, N. J.

Application September 12, 1947, Serial No. 141,352

Term of patent 3½ years

(Cl. D34—5)

To all whom it may concern:

Be it known that we, Martin Siegel, William S. Hosek, and Frank L. Boucher, citizens of the United States, residing at Newark, Bloomfield, and Millington, respectively, in the counties of Essex, Essex, and Morris, respectively, all in the State of New Jersey, have invented a new, original, and ornamental Design for a Game Board, of which the following is a specification, reference being had to the accompanying drawing, forming part thereof.

The figure is a top plan view of a game board, showing our new design.

The thickness of the game board is conventional.

The dominant features of our new design are shown in solid lines in the drawing.

We claim:

The ornamental design for a game board, as shown and described.

MARTIN SIEGEL.
WILLIAM S. HOSEK.
FRANK L. BOUCHER.
